UNITED STATES PATENT OFFICE.

WILLIAM S. GRAFTON, OF WHEELING, WEST VIRGINIA, ASSIGNOR TO THE WHEELING CORRUGATING COMPANY, OF SAME PLACE.

DESIGN FOR A METALLIC MOLDING.

SPECIFICATION forming part of Design No. 23,047, dated February 6, 1894.

Application filed January 8, 1894. Serial No. 496,193. Term of patent 7 years.

To all whom it may concern:

Be it known that I, WILLIAM S. GRAFTON, a citizen of the United States, residing at Wheeling, in the county of Ohio and State of West Virginia, have invented and produced a new and original Design for a Metallic Molding, of which the following is a specification, reference being had to the accompanying drawing, forming part hereof, which shows a metallic molding designed according to my invention.

My design consists of a metallic molding A, divided into equal parts or subdivisions B, by ribs or ridges a, extending from one side of the molding to the other. The ribs a, are joined at their ends by similar ribs or ridges a'. At the intersections of the ridges a and a', there are convex projections a², with concave centers a³. Similar concaved projections are also arranged in the ribs or ridges a, midway between their ends. The central portion C, of each section B, is raised above the edges c of the molding, and the edges are joined to the central portion by inclined 25 curved sides c'.

In each of the central portions C, there is an oval or egg-shaped depression D, surrounded by an oval rib d, from which radiate a series of straight depressions d', joining 30 another oval or oblong rib d². The opposite ends of this oval rib join the concaved pro-

jections a² in the central portion C. Another oval rib d³ surrounds the oval rib d², and in the four corners of the central portion C, there are triangular projections E. Each of 35 the inclined sides c' is ornamented with a triangular projection F, having an oblong depression f, and a series of curved ribs or projections f', radiating from the central portions C, and joining each other at their outer 40 ends near the edges of the side portion c'.

The ornamentations in all the central portions C, and in all the side portions c' are alike.

The essential feature of my design is a metallic molding for each section of the central portion ornamented with a central oval depression surrounded by an oval rib from which radiate straight depressions, surrounded by a series of oval ribs and each side portion having a triangular projection surrounded by curved ribs or ridges joined at their outer ends.

I claim—

The design for a metallic molding herein shown and described.

In testimony whereof I have hereunto subscribed my name.

WILLIAM S. GRAFTON.
